MYLES A. CONNELLY, OF YOUNGSTOWN, OHIO.

APPARATUS FOR LEVELING AND TAMPING CONCRETE ROAD-BEDS.

1,238,497.

Specification of Letters Patent. Patented Aug. 28, 1917.

Application filed February 26, 1917. Serial No. 150,906.

To all whom it may concern:

Be it known that I, MYLES A. CONNELLY, a citizen of the United States of America, and resident of Youngstown, county of Mahoning, and State of Ohio, have invented certain new and useful Improvements in Apparatus for Leveling and Tamping Concrete Road-Beds, of which the following is a specification.

This invention relates to machines for spreading and tamping concrete or other monolithic materials in road building, and it has for its primary object to provide a machine whereby the plastic material deposited may be evenly spread and tamped to form a base for the brick in the construction of brick-paved roads.

A further object is to provide a machine of the character mentioned having such width that the full width of the roadway under construction is thereby traversed and acted upon, thus providing for the formation of a surface devoid of the irregularities which are commonly incident to the use of a spreader or roller which is of relatively narrow width and which, consequently, requires a number of parallel passes to complete the surfacing of the roadway.

A still further object is to provide a spreading and tamping machine which is capable of adjustment to any width necessitated by the width of the roadway under construction.

Another object within the contemplation of the invention is to provide means for abrading or slightly roughing the surface following the tamping of the latter.

With these and other incidental objects in view, the invention resides in the features of construction; arrangement of parts and combinations of elements which will hereinafter be exemplified, reference being had to the accompanying drawings, in which—

Figure 1 is a view partly in top plan and partly in horizontal section, showing an embodiment of the invention;

Fig. 2 is a transverse section on line 2—2, Fig. 1;

Fig. 3 is an enlarged fragmentary sectional view in perspective, illustrating various features of the invention; and—

Fig. 4 is an enlarged section on line 4—4, Fig. 1.

Referring to said drawings, in which like designating characters distinguish like parts throughout the several views—

1 indicates each of two opposite frame members mounted upon suitable wheels or rollers 2 which are designed, preferably, to travel upon tracks constituted by longitudinal road-defining forms 3. Said members are rigidly connected by a cross-member which is preferably composed of two channel irons 4 disposed flatwise and having their outer ends mounted upon said members. The inner ends of said channel irons are disposed in telescopic relation and rigidly connected by bolts. Rigidly mounted on the under side of said cross-member and also disposed in telescopic relation is a pair 60 of vertically disposed members 5 which may also be of channel form and which constitute supports for a vertically disposed scraper blade or templet 6 which latter may be a single plate or may be composed of a plurality of sections, as desired. Suitable braces, as 7, are disposed between the members 5 and the frame members 1 for maintaining a rigid relation. Rollers 8 and 9 are carried by each of said members 1, the same 70 being designed to ride against the inner faces of the forms 3 for reducing to a minimum the frictional resistance to travel of the machine which would otherwise be encountered in the event that one end of the latter should be advanced slightly ahead of the other. Said rollers are mounted upon vertical spindles 10 carried by the inner ends of bolt-like stems 11 which are projected through the members 1. Said stems 80 carry compression springs 12 thereon between a washer 13 and the outer face of said member 1, thus providing for holding said rollers under a yielding tension in engagement with the forms. 85

Bolted to the rear faces of the blade-supporting members 5 is a plurality of spaced lugs 14 to which are pivotally connected the front ends of short links 15 to the rear ends of which are pivotally connected the front ends of frame sections 16, hereinafter termed "front-roll bearing sections", which sections are arranged in pairs. The sections composing each pair are rigidly connected at their rear ends to the transverse connecting portion of a U-shaped frame section 17, hereinafter termed "rear-roll bearing sections". Each of said rear-roll bearing sections has a bearing 18 in each of its parallel members in which is journaled a shaft 19 carrying a tamping roller 20. Also, each of the front-roll bearing sections 16 except 95 100 105 110

the two endmost thereof has a bearing 21 therein in which is journaled a shaft 22 carrying a tamping roller 23. Said rollers 23 have their opposite ends journaled in the 5 adjacent bearing sections of adjacent pairs of said sections, as shown, while each of the rollers 20 is disposed within the embrace of a section 17 and has its opposite ends journaled in the opposite members of such section. Consequently, the disposition of the 10 rear rollers 20 is such that they break joints with the front rollers 23, providing for the tamping of the entire width of the roadway under construction at a single pass of 15 the machine.

Pivottally connected to the free rear end of each of the parallel members of the rear-roll bearing sections is one end of a link 24 which has its opposite end attached to a drag 20 25 which is designed to follow the rollers for roughening slightly the surface of the tamped material to render the same better adapted for receiving paving bricks in seated position thereon. While said drag may 25 be of any suitable character and may be made of any appropriate material, I prefer to employ a length of heavy leather belting, such having been found admirably adapted for the purpose. Said drag is made in two 30 or more sections having their adjacent ends disposed in overlapped relation to adapt the same for adjustment with other parts of the machine to suit the width of the roadway being acted upon.

35 Suitably mounted upon the front face of the scraper-blade supports 5 adjacent to the outer ends of the latter is one end of a forwardly and outwardly inclined scraper 26 which has a tapered form to permit its front 40 end to underlie the adjacent frame member 1, said scraper being designed to spread the material which lies close to the adjacent form 3. A bolt 27 is projected through said scraper at a suitable point and through a 45 portion of the adjacent brace 5 and carries thereon a compression spring 31 whereby said scraper is yieldingly maintained in a position wherein its front end scrapes against the inner face of said form 1.

50 Suitable means is provided whereby the height of the frame members 1 and of the attached parts, including the scraper blades or templets 6, may be adjusted to regulate the working level of the latter, said means 55 preferably comprising bearing blocks 29 in which are mounted shafts 32 upon which the supporting wheels or rollers 2 are rotatable. Said bearing blocks 29 are vertically movable in yoke-like guideways 28 attached to 60 said frame members and are swiveled upon the ends of vertically disposed adjusting screws 30.

The ends of the foremost of the shafts 32 are preferably of squared form and project 65 outward beyond the guideways 28, the same

constituting fulcrums upon which a pair of connected parallel members 33^a forming parts of a lever 33 of the first class may rest, said members being pivotally mounted upon opposite sides of the frame member 1 at points 70 rearward with respect to the location of said shaft 32. As is obvious, upon the application of sufficient force to the outer end of the lever 33, the rear end of the frame member 1 may be elevated slightly to effect 75 a slight shifting, or teetering, of said frame member, as for relieving binding between said frame member and the form 3.

As is obvious, due to the non-rigid or pivotal mounting of the roll bearing sections 80 16 and 17, each of the rollers 20 and 23 acts more or less independently of the others in following the scraper-blades. When it becomes desirable to increase the tamping pressure of the rollers, the roll bearing sections 85 16 and 17 may serve as supports for plates or bars (not shown) which may be disposed thereon at points between adjacent alined rollers for supporting sand bags or the like whereby the weight of the machine may be 90 increased.

To adjust the machine for use upon roads of different widths, the telescoping and overlapped parts hereinbefore mentioned may be extended or shortened, and one or more 95 rollers with the necessary supporting sections therefor may be added or removed, as required, such additions or removals being preferably made at or near the middle of the width of the machine.

100 It will be apparent that the machine described is readily susceptible to various changes and alterations in the construction and arrangement of its parts. It will therefore be understood that the invention is not 105 confined to a strict conformity with the showing herein specifically made, but the details of construction may be changed and modified to the extent that such changes and modifications mark no material departure 110 from the salient features of the invention as defined in the appended claims.

115 What is claimed is—

1. In a device for leveling and tamping concrete paving beds, a frame disposed across the road bed and adapted for adjustment to varying widths, scraping blades or templets carried by said frame, members pivotally connected to said frame and extending rearward therefrom, said members being arranged in pairs, tamping rollers journaled on said members, U-shaped members disposed rearward of said rollers and connected to the rear ends of said pivoted members, and a tamping roller journaled in each 120 of said U-shaped members.

125 2. In a device for leveling and tamping concrete paving beds, a frame disposed across the road bed and adapted for adjustment to varying widths, scraping blades or 130

- templets carried by said frame, members pivotally connected to said frame and extending rearward therefrom, said members being arranged in pairs, tamping rollers 5 journaled on said members, U-shaped members disposed rearward of said rollers and connected to the rear ends of said pivoted members, a tamping roller journaled in each of said U-shaped members, and a sectional 10 drag pivotally connected to the last-mentioned members.
3. In a device for leveling and tamping concrete paving beds, a frame disposed across the road bed and adapted for adjustment to varying widths, scraping blades or 15 templets carried by said frame, members pivotally connected to said frame and extending rearward therefrom, said members being arranged in pairs, tamping rollers 20 journaled on said members and disposed between adjacent pairs, a plurality of U-shaped members disposed rearward of said rollers, each having the rear ends of a pair of said pivoted members rigidly attached 25 thereto, and a tamping roller journaled between the lateral members of each of said U-shaped members.
4. In a device for leveling and tamping concrete paving beds, a frame disposed 30 across the road bed and adapted for adjustment to varying widths, scraping blades or templets carried by said frame, members pivotally connected to said frame and extending rearward therefrom, said members being 35 arranged in pairs, tamping rollers journaled on said members and disposed between adjacent pairs, a plurality of U-shaped members disposed rearward of said rollers, each having the rear ends of a pair 40 of said pivoted members rigidly attached thereto, and a tamping roller journaled between the lateral members of each of said U-shaped members, the location of the last-named members being such that the tamping 45 rollers journaled therein break joints with the first-mentioned tamping rollers.
5. In a device for leveling and tamping concrete paving beds, a pair of oppositely disposed frame members, telescoping members 50 disposed across the road bed and connecting said frame members, scraper blades or templets supported by said telescoping members, said templets being adapted for relative adjustment, bars pivotally connected to said telescoping members and extending rearward therefrom, a plurality of tamping rollers journaled on said bars, a 55 plurality of tamping rollers disposed rearward of the first-mentioned rollers and breaking joints with the latter, members in which the last-mentioned rollers are journaled, said members being connected to said bars, and anti-friction means preventing binding of the parts of the frame with road-defining forms.
6. In a device for leveling and tamping concrete paving beds, a main frame adapted for extending across the roadway, scraping blades or templets carried by said frame, a plurality of independent roll-bearing frame 60 sections pivotally connected to and extending rearward from said main frame, and tamping rollers mounted in said frame sections.
7. In a device for leveling and tamping concrete paving beds, a pair of oppositely disposed frame members, telescoping members disposed across the road bed and connecting said frame members, scraper blades or templets supported by said telescoping members, said templets being adapted for relative adjustment, bars pivotally connected to said telescoping members and extending rearward therefrom, a plurality of tamping rollers journaled on said bars, a plurality of tamping rollers disposed rearward of the first-mentioned rollers and breaking joints with the latter, members in which the last-mentioned rollers are journaled, said members being connected to said bars, and anti-friction means preventing binding of the parts of the frame with road-defining forms.
8. In a device for leveling and tamping concrete paving beds, a pair of oppositely disposed frame members, telescoping members disposed across the road bed and connecting said frame members, scraper blades or templets supported by said telescoping members, said templets being adapted for relative adjustment, bars pivotally connected to said telescoping members and extending rearward therefrom, a plurality of tamping rollers journaled on said bars, a plurality of tamping rollers disposed rearward of the first-mentioned rollers and breaking joints with the latter, members in which the last-mentioned rollers are journaled, said members being connected to said bars, and forwardly and outwardly extending yieldably mounted scrapers carried by said telescoping members adjacent to the outer ends thereof.
9. In a device for leveling and tamping concrete paving beds, a main frame adapted for extending across the roadway, scraping blades or templets carried by said frame, a plurality of independent roll-bearing frame sections pivotally connected to and extending rearward from said main frame, and tamping rollers mounted in said frame sections.
10. In a device for leveling and tamping concrete paving beds, a pair of oppositely

concrete paving beds, a frame, scraping blades or templets carried by said frame, a plurality of pairs of members pivotally connected to and extending rearward from said frame, tamping rollers journaled on said members, members connected to and extending rearward from the first-mentioned members, and tamping rollers jour-

naled in the last-mentioned members, said rollers being arranged to break joints.

In testimony whereof, I affix my signature in presence of two subscribing witnesses.
